UNITED STATES PATENT OFFICE

JOHN POUNTNEY UDAL, OF SELLY PARK, BIRMINGHAM, ENGLAND

PRESS GUARD

Application filed April 1, 1931, Serial No. 526,942, and in Great Britain May 29, 1930.

This invention relates to the hand guards employed in combination with such machines as presses, stamps, hammers and the like, and particularly the guards of the kind described and claimed in the specification of my previous U. S. Patent No. 1,545,929.

The object of the present invention is to provide an improved guard adapted for use more particularly with large presses. In such machines it is desirable that the guard when in its inactive position shall occupy a position well above the space through which the operator feeds the work pieces to the tools. By the present invention I am able to satisfy this condition in a very simple and convenient manner, and, at the same time, retain the advantageous features of my previous patented guard.

The essential features of my former guard comprise a pair of lever systems one of which is pivoted on the other. One of the lever systems is pivoted on a stationary part of machine, and the other which carries the hand striking member is connected to a convenient part of the machine by a link or other constraining means. Motion is imparted from any convenient part of the machine to the lever system pivoted on a stationary part of the machine.

The present invention comprises the pivoting of one of the lever systems on the movable plunger or like part of the machine, and the connecting of this lever system to a stationary part of the machine through the medium of a pivotal link, or an equivalent actuating connection.

In the two accompanying sheets of explanatory drawings:—

Figure 1 is a front elevation and Figure 2 an end elevation showing in the inner position a press guard constructed in accordance with this invention.

Figure 3 is an end view showing the guard in the outer or extended position.

In carrying the invention into effect as shown I carry by means of brackets *a* on the plunger *b* of the press or other suitable moving part of the machine, a cross-shaft *c* to which are secured a pair of levers *d*. These levers may be interconnected by cross

rods *e*, and they form the first of the two lever systems of my guard. To one end of the same cross-shaft *c* there is secured another lever *f*, the free end of which is connected by means of a pivoted link *g* to a bracket *h* on a convenient stationary part of the machine. It will be apparent that reciprocation of the plunger, and, consequently, of the cross-shaft *c* carrying the first lever system, will be accompanied by oscillation of the lever system *d* relatively to the front of the machine. At the lower end of the first lever system *d* there is provided another cross-shaft *i* which carries another pair of levers *j* forming the second lever system. These levers are interconnected by cross bars *k*, and at their lower end they carry a hand striking member *l*. The upper end of one of the levers *j* is extended, and to this extension there is pivotally attached another link *m* serving as a constraint, this link being also connected to a swivel piece *n* pivoted on one of the brackets *a*.

When the plunger is in its upper position the whole of the guard mechanism occupies an inner position well above the space through which the work pieces are fed between the upper and lower tools respectively carried on the plunger *b* and base *p* of the machine as shown in Figures 1 and 2. During the descent of the plunger and in the initial part of such movement the first lever system *d* is caused to swing outwards, and by this action a rapid swinging movement is given to the second lever system *j* whereby the hand striking member *l* not only descends with the plunger, but also moves rapidly in the outward direction towards the operator as shown in Figure 3. Should the operator's hand or arms be in a dangerous position during this movement of the plunger they will be caught by the hand striking member and moved in a forward direction clear of the descending tool.

The invention is not limited to the example above described nor to any particular subordinate constructional or mechanical features, but in all cases the first lever system is pivoted on the plunger or like part of the machine, and the guard receives its

motion directly from that part. Thus, instead of connecting the upper guard portion to the fixed part of the machine by a link *g*, any other suitable connection may be employed whereby the relative movement of the plunger and the stationary part of the machine can be utilized to produce the required swinging of the guard.

Having thus described my invention what 10 I claim as new and desire to secure by Letters Patent is:—

A press guard for a power press having a reciprocating plunger comprising brackets on said plunger, a cross-shaft mounted on 15 said brackets, a primary guard member mounted on said cross-shaft, a lever attached to said cross-shaft, a link pivotally attached to said lever and a stationary part of the press, a second guard member pivoted on the 20 primary guard and provided at its lower end with a hand striking member, an extension on said secondary guard member and a link having one end pivoted to said extension and the other end pivotally mounted on one of 25 said brackets.

In testimony whereof I have signed my name to this specification.

JOHN POUNTNEY UDAL.
